US0D1108365S

(12) United States Design Patent (10) Patent No.: US D1,108,365 S
(45) Date of Patent: * Jan. 6, 2026

(54) WIRELESS POWER BANK

(71) Applicant: SHENZHEN ZOWEE TECHNOLOGY CO., LTD, Shenzhen (CN)

(72) Inventor: Aidong Hu, Guangdong (CN)

() Term: 15 Years

(21) Appl. No.: 35/523,520

(22) Filed: Nov. 19, 2024

(80) Hague Agreement Data

Int. Filing Date: Nov. 19, 2024

Int. Reg. No.: DM/243054

Int. Reg. Date: Nov. 19, 2024

Int. Reg. Pub. Date: Jan. 10, 2025

(51) LOC (15) Cl. 13-02

(52) U.S. Cl.

USPC D13/108

(58) Field of Classification Search

USPC D13/108, 110, 107, 103, 112, 118, 119, D13/184, 199

CPC H02J 7/00; H02J 7/0042; H02J 7/0044; H02J 7/0045; H02J 7/0047
